UNITED STATES PATENT OFFICE.

CLINTON B. FERGUSON, OF NEWTONVILLE, MASSACHUSETTS.

DESIGN FOR A COMBINED CANDELABRUM AND ELECTRIC TERMINAL.

56,248.

Specification for Design.

Patented Sept. 7, 1920.

Application filed November 7, 1919. Serial No. 336,479. Term of patent 14 years.

To all whom it may concern:

Be it known that I, CLINTON B. FERGUSON, a citizen of the United States, residing at Newtonville, in the county of Middlesex and State of Massachusetts, have invented a new, original, and ornamental Design for a Combined Candelabrum and Electric Terminal, of which the following is a specification, reference being had to the accompanying drawings.

The figure is a perspective view of a decorative center-piece for dining room tables combining a candelabrum and electric terminal, embodying my new design.

The essential feature of my design consists in the general proportions of the center-

piece which comprises a low, broad flat base, from the upper surface of which rise two symmetrically placed light fixtures forming the candelabrum, and in which is set a multiple electric receptacle.

It will be understood that widely varying forms of shades for the light fixtures, other than those herein depicted, may be employed without changing my design.

Having thus described my invention, I claim:

The ornamental design for a combined candelabrum and electric terminal, substantially as shown and described.

CLINTON B. FERGUSON.
